UNITED STATES PATENT OFFICE.

CARL E. I. LUNDBERG, OF SPOKANE, WASHINGTON.

GAME APPARATUS.

No. 870,041.

Specification of Letters Patent.

Patented Nov. 5, 1907.

Application filed February 28, 1907. Serial No. 359,922.

To all whom it may concern:

Be it known that I, CARL E. I. LUNDBERG, a citizen of the United States, residing at Spokane, in the county of Spokane and State of Washington, have invented 5 certain new and useful Improvements in Game Apparatus, of which the following is a specification.

This invention relates to amusement devices being designed to provide an apparatus for playing indoors the popular game of base ball and presenting all the 10 phases and excitement incident to the outdoor game, particularly when the players are skilled in the delivery and batting of the ball and in the manipulation of the field pieces.

For a full description of the invention and the 15 merits thereof and also to acquire a knowledge of the details of construction and the means for effecting the result, reference is to be had to the following description and accompanying drawings.

While the invention may be adapted to different 20 forms and conditions by changes in the structure and minor details without departing from the spirit or essential features thereof, still the preferred embodiment is shown in the accompanying drawings, in which:

25 Figure 1 is a plan view of the game apparatus embodying the invention. Fig. 2 is a detail perspective view of the corner portion of the board provided with the bat and home base. Fig. 3 is a detail perspective view of the corner portion of the game board equipped 30 with the projecting means, whereby delivery of the ball to the batsman is effected. Fig. 4 is a detail view of the bat.

Corresponding and like parts are referred to in the 35 following description and indicated in all the views of the drawings by the same reference characters.

The board 1 may be of any size and is approximately 40 square and about three feet each way. The infield is located at one corner of the board and is inclosed between the lines 2, 3, 4, and 5. The home base is located 45 at one corner of the infield and is represented by means of a stripe painted, or otherwise provided upon the board. At each of the corners 2, 3 and 4 squares are provided representing the bases, the square 3 being first base, the square 2 second base, and the square 4, 50 third base. A square 7 is located on the line 2-4 a short distance from the square of second base 2 for reception of the runner on second base so that no obstruction of delivery of the ball to the batsman may result as would be the case if the runner occupied the square 2 which is in line with the pitcher and batter.

The line 5-3 is projected to 8 to provide the foul 55 line 5-8. The line 5-4 is similarly projected to 9 forming the other foul line 5-9. The foul lines are located a short distance from the proximal guards, or inclosing means 10 at the proximal edges of the board. The corner of the board adjacent to the home base is

cut away, the guard fitted thereto constituting the back stop.

The bat 12 consists of a strip of suitable length and width and may be of any material. The striking face 60 of the bat is preferably covered with felt, or some such like material to deaden the blow, or impact of the bat with the ball, and to deaden the sound. The bat is thickened at one end, at 13, and has a pin 10 in line with the thickened end 13 and projected from the 65 lower edge of the bat to enter an opening or cut away portion 30 in the board. This opening 30 is of a size to permit of the pin 10 having a limited play, whereby the bat may be slid half an inch, more or less, upon the board when playing to get the best results. Pieces 70 of leather, felt or like material 31 are attached to the lower edge of the bat to prevent marring the surface of the board by movements of the bat thereon.

In manipulating the bat the enlarged portion at one end of the same is grasped between the thumb and 75 forefinger of the hand and the bat both shifted laterally and swung about its pivot to strike the ball projected toward the same.

The board at the corner diagonally opposite to the bat and home base is cut away and the guard, or inclosing means 10, is set in a short distance from the corner portion of the board so as to leave a platform 14 exterior thereto to form a support for the hand and to receive the ball projecting means.

An opening 15 is provided in the guard 10 to receive 85 the ball 16, the latter consisting of a sphere, preferably of steel. The ball is adapted to be projected by suitable means, such as a rubber band 17 which is drawn outward and suddenly released. The rubber band or elastic 17 is arranged opposite the opening 15 90 and exterior to the guard and is supported upon two pins 18 let into the guard and located upon opposite sides of the opening 15, or said rubber band may be supported by other means.

It is understood that the ball may be delivered by 95 striking the elastic 17, the latter serving to modify the force of such blow to such an extent as to prevent a too rapid movement of the ball across the board.

Circles 19, 20, 21, 22, 23, 24 and 25 are imprinted, or otherwise supplied to the surface of the board and represent the space on which the fielders, such as the first, second and third basemen, the short stop, the right, left and center fielders can be moved. Upon each of the circles is placed a man, or game piece 26, the same consisting of a flattened disk such as the usual 100 piece used in playing the game of checkers, the game pieces 26, representing the fielders who occupy any place in their respective circles; the game piece of the center field circle 24 is placed to one side so as not to obstruct proper delivery of the ball to the batter. 105

The guard 10 may be a strip attached to the board, either to the edge, or to the top side thereof, or may

consist of a flange according to the construction of the board. The sole purpose of the guard is to prevent displacement of the ball from the board either when struck by the bat or when rebounding when delivered from 5 the pitcher's position. Said guard is lined with felt or some like substance on the inside, so as to deaden the sound when the ball hits the guard.

It is to be understood that the batter is provided with a number of game pieces, usually 4, the same being indicated by the reference numeral 27.

The following is a description of playing the game and the value of the respective pieces.

1. The pitcher sits back of the ball and tries to shoot the ball over the home base. If the ball goes over the 15 home base 5, it constitutes a strike, but if it goes to one side of the home base 5, it constitutes a ball.

2. If the ball is hit anywhere outside of the foul line, it constitutes a foul, which also constitutes a strike. If the ball goes no further than the infield, it also constitutes a foul for the reason that otherwise, the batter can hold the bat still, and the ball will generally stop in the infield. If the ball goes to the guard or stops in the 20 outfield without touching a game piece 26, it constitutes a fair hit, or one base hit.

3. The game pieces 26 may be moved anywhere inside 25 of their respective circles by the pitcher; if he succeeds in having a game piece touch the ball after it is batted by the batter it constitutes an out, but if the pitcher moves the game piece outside of the circle and touches the ball with said game piece, or if the ball hits any 30 part of the pitcher's clothing, or hand, it gives the batter a two base hit. If the ball touches one game piece and bounds off and touches another game piece, it constitutes a double out, providing there is a man on a base, 35 the man supposed to be batting and the man on first base or nearest the same being out; triple out the same way. The game pieces can be placed anywhere in their respective circles with the exception of the center fielder, which must be placed to the side so as to allow 40 the pitcher to shoot the ball to home base.

4. The batter's game pieces 27 are the same size as game pieces 26. If a fair hit is made one of his game pieces is put on first base, if another fair hit is made that man is put on second base (this man is put on the 45 square marked 7 instead of the real second base 2 so that it will not be in the way of the pitcher when he shoots the ball) and another man is put on the first base.

If the pitcher throws four balls before the batter is out, the man goes to first base (as in regular base ball).

50 If the pitcher gets three strikes on the batter he is out.

There are three outs to an inning, after which the pitcher bats and the batter goes to pitch (shooting the ball).

If the ball is batted through the opening between the strips 15 it constitutes a home run; all men on bases 55 coming in.

When a man makes the circuit and touches home base it counts one score for the batter.

It will be seen that this is very much like the regular outdoor base ball game. The pitcher who is skilled 60 in shooting the ball over the base and is quick to judge where the ball is going and can get his game piece in the way quickly can keep the batters score very low. And the batter who has a good eye can place the ball where he is more apt to make a safe hit preferably 65 within the circles of first, second, third basemen and short stop but without hitting said men, will make more scores as the pitcher will have to be exceptionally quick to stop the ball when it goes near those circles. Consequently, it will be seen that the skilled man will 70 win nearly every time.

Having thus described the invention, what is claimed as new is:

1. The combination of a board, game pieces upon the board, a bat mounted upon the board and having a shift- 75 able pivot, and means for delivering a ball to the bat.

2. The combination of a board, game pieces upon the board, the said board having an opening formed therein, a bat provided with a pivot pin received loosely within the opening to admit of the pivot point of the bat being 80 shifted, and means for delivering a ball to the bat.

3. The combination of a board having an opening formed therein, game pieces upon the board, a bat having one end thereof enlarged and the enlarged portion being formed with a pin received loosely within the opening in 85 the base, and means for delivering a ball to the bat.

4. The combination of a board, a guard surrounding the board, one portion of the guard being spaced from an edge of the board to provide a rest for the ball and having an opening formed therein, game pieces upon the board, a bat mounted upon the board, and means outside of the guard for delivering a ball through the opening to the bat. 90

5. The combination of a board, a guard surrounding the board and having an opening formed therein, game pieces upon the board, a bat mounted upon the board, and an elastic applied to the guard upon opposite sides of the before mentioned opening therein and adapted to deliver a ball through the opening to the bat. 95

In testimony whereof I affix my signature in presence 100 of two witnesses.
